[57] CLAIM

The ornamental design for an electrical equipment housing, as shown and described.

DESCRIPTION

FIG. 1 is a perspective view of an electronic equipment housing;

FIG. 2 is a front plan view of the electronic equipment housing;

FIG. 3 is a bottom plan view of the electronic equipment housing; and,

FIG. 4 is a right side plan view of the electronic equipment housing.

The rear, top and left surfaces not shown in the drawings form no part of the claimed design.
